UNITED STATES PATENT OFFICE.

DWIGHT W. CUSTER, OF NEW YORK, N. Y., ASSIGNOR TO MATTIE R. CUSTER, OF NEW YORK, N. Y.

GARMENT-STRETCHER.

1,279,281.

Specification of Letters Patent. Patented Sept. 17, 1918.

Application filed March 27, 1915, Serial No. 17,319. Renewed August 21, 1918. Serial No. 250,896.

To all whom it may concern:

Be it known that I, DWIGHT W. CUSTER, a citizen of the United States, residing at the borough of Manhattan, in the city, county, and State of New York, have invented certain new and useful Improvements in Garment-Stretchers, of which the following is a specification, reference being had therein to the accompanying drawings, 10 which form a part thereof.

My invention relates to garment stretchers and more particularly to a type of knock-down structures adapted for use in shaping trousers.

Heretofore there has been extensively used a variety of different trouser stretchers adapted when not in use, to be folded together, or taken apart and the parts packed together in as small compass as the number 15 and size of the various parts of the device will permit. Ordinarily those stretchers which are adapted to be folded together, while capable of being quickly extended for use, are bulky when folded and thus are not 20 of a form which will admit of their being packed in a traveling bag without a material waste of space within the bag. Those structures which are taken apart when not 25 in use, while occupying a sufficiently small space to facilitate their being readily packed in a traveling bag are not capable of being 30 quickly extended. In neither of the types of stretchers above referred to, is it feasible 35 to fold the stretcher with the trousers in place therein; and have the stretchers remain operative to form the trousers while thus folded with the stretcher.

A garment stretcher made in accordance with my invention is made of a plurality 40 of sections foldable one within another in a manner to permit the whole device to be brought within the confines of the largest section, thus not only affording a small, compact article when folded but permitting the 45 stretcher to be instantly extended to its full length when it is desired to place trousers therein. The sections at the opposite ends of the stretcher are provided with clamp bars, and adjoining sections are provided 50 with co-operating means for preventing the collapse of the stretcher under the stresses thereon from the garment or garments being

stretched. The clamp bars are provided with securing means so constructed as to permit the adaptation of the clamp to garments differing in thickness, or for use with two or more pairs of trousers. Succeeding 55 stretcher sections must be of gradually reduced dimensions so that each section will fold within the adjoining sections, and each 60 section is centered with relation to its adjoining section in a manner to insure the desired alinement of all sections when the 65 stretcher is extended. The fittings used for thus properly spacing the sections with relation to each other, may be, and preferably are used for preventing movement of the 70 section toward the trousers therein. The manner of pivotally uniting the sections is such as to not only insure permanency in 75 the structure but to afford rails over which garments not being stretched may be hung. The stretcher is made almost entirely of 80 wood, such metal fittings as are used being capable of production at small cost, and of 85 being quickly assembled in the stretcher, thus permitting the economic production of 90 the stretcher in its entirety.

The invention consists primarily in a garment stretcher embodying therein a plurality of sections each having parallel side bars, said bars of each section being shorter 85 in length than, and positioned within, the side bars of the adjoining section, means pivotally connecting the side bars of adjoining sections, a cross bar carried by each end section, a clamp bar adapted to bear toward each end bar, and means adapted to close and hold said clamp bar; and in such other 90 novel features of construction and combination of parts as are hereinafter set forth and described and more particularly pointed out in the claims hereto appended.

Referring to the accompanying drawings:—

Figure 1 is a perspective view of a garment stretcher extended to its full length a pair of trousers being indicated therein in dotted lines;

Fig. 2 is a view thereof on a larger scale 100 showing the stretcher folded together; and

Fig. 3 is a detail view, upon a still larger scale, of one end of a clamp bar and its co-operating cross bar and a portion of the side

bar of one of the end sections, with the closing and holding mechanism for the clamp bar.

Like letters refer to like parts throughout the several views.

In the embodiment of my invention shown in the drawings, the garment stretcher is shown as being composed of three sections, the largest of which is of a dimension to 10 permit the device to be conveniently packed in a suitcase or traveling bag. The number of sections employed, however, is immaterial although I preferably employ only three as such minimizes the cost of the material entering into the article and the labor of assembling. At least three sections, however, should be used in order to make the folded article compact. Each of the sections has parallel side bars $a-a'$; $b-b'$ and $c-c'$ the 15 side of each section being shorter than those of the next adjoining section, so as to permit the sections to be folded one within the other as shown in Fig. 2. The ends of the side bars $a-a'$ overlap and are positioned 20 within, the ends of the side bars $b-b'$ and are pivotally connected thereto; and the other ends of the side bars $b-b'$ overlap and are positioned within the side bars $c-c'$ 25 and are pivotally connected thereto.

These side bars are preferably made of 30 wood and the pivotal connection is secured by means of rungs $d-d'$ extending completely across each section and projecting through openings adjacent the overlapped 35 ends of adjoining side bars. By this means, I not only properly distance the side bars of each section, but afford a rack within the frame over which articles of apparel may be hung.

The bars $a-a'$ and $c-c'$ of the end sections each carry a cross bar e and f . Mounted upon said side bars adjacent said cross bars respectively are movable clamp bars $g-h$ adapted to bear toward and hold 45 a garment firmly against the cross bars $e-f$.

The cross bar e is provided with a pivotal hook i by means of which the stretcher may be hung in a wardrobe. When the stretcher 50 is not in use this hook may be folded against the cross bar e in the manner shown in Fig. 2.

Each clamp bar $g-h$ is pivotally connected to the side bar by means of a metallic fitting which will serve to draw said clamp bar toward the cross bar and lock it in position with relation thereto. This fitting is so constructed that the clamping action of the bars $g-h$ may be controlled to adapt the 55 clamp for use with different thicknesses, or a different number of thicknesses, of material. Each of the said fittings is similar to the other and a description of but one of them will be entered into.

Each of said clamp bar fittings comprises

a bracket j one end of which is adapted to be pivotally connected to the side bar and the other end of which is provided with an ear j' adapted to be connected with the clamping bar and a stepped catch j^2 projecting at an angle from the end of the clamping bar upon substantially the plane of the axis of the screw j^3 connecting the ear j' with said bar. Mounted upon the side bar of the end section is a bearing plate k having mounted therein a lever l having looped 70 crank bearings l' and trunnions l^2 mounted in said bearing plate. Pivotally mounted in the bearings l' is a loop m adapted to engage 75 in any of the notches in the catch j^2 .

To properly position the side bars of each section with the side of the adjoining section and preserve the alinement thereof under all conditions, I provide a distance piece or washer which is not only capable 80 of yielding sufficiently to permit the free movement of the sections relative to each other but may also be, and preferably is used, as a locking means to prevent the said sections moving toward the trousers when 85 the device is in use. Each of these distance pieces or washers consists of a troughed section o one edge o' of which is turned over to bear upon the face of its side arm, and the other edge o^2 of which projects beyond 90 the face of the adjoining side arm and is slotted at o^3 as shown to form a keeper for the pivotal plate p mounted upon the section o . This pivotal plate p is adapted to prevent pivotal movement of the stretcher 95 section in one direction while admitting slight movement thereof in the other direction. The distance pieces o are each pivotally mounted upon the rungs d or d' so as to be able to move freely with their side bar. 100

The flange o' bearing upon the side bar insures permanency in the relation of the spacing and the said side bar. It will be observed that the said distance pieces are held in position by means of the said rungs 110 d or d' although, if desired, the pivotal support for the plate p may be a screw passing through the turned edge o' and engaging the side bar. The spacing of the side bars of one section away from those of the adjoining section, permits the graduation in the width of the device necessary to allow it to be folded together as shown and at the same time affords proper clearance for the mechanism carried by the smaller 115 end section. The side bars $a-a'$ and $c-c'$ are provided with wear pieces q against which the plates p are adapted to bear.

The operation of the herein described device is substantially as follows:

When the garment stretcher is not in use, the various plates p are swung upon their pivots and brought within the surface of the turned edge o' of the distance pieces o . The side bars $a-a'$ are then turned upon the 120 125 130

rung d so as to bring these bars between the bars $b-b'$ which bars are then turned upon the rung d' to bring the two smaller sections within the side bars $c-c'$ and the cross bar f .
 5 When the device is so folded it will have a uniform thickness throughout, which thickness will be that of the section formed by the bars $c-c'$, the cross bar f and the clamp bar h . When so folded, the stretcher may
 10 be readily packed in an ordinary hand bag, or dress suit case and the portion within the bars $a-a'$ and e and the rung d may be used for packing articles. The hook i when the device is not in use is folded upon the
 15 cross bar e in the manner shown in Fig. 2.
 When it is desired to stretch trousers for the purpose of forming or creasing them, the device may be instantaneously extended by merely lifting it by means of the cross
 20 bar e or the hook i thereon, the weight of the various parts serving to cause them to drop to position. The hook i is then used to suspend the stretcher. The clamp bars $g-h$ are then released by swinging the lever l toward said bars, thus permitting the loop m to be removed from the catch j^2 . The bottom of the trousers is then inserted between the bar g and the bar e and the bar g is closed by hand upon said ends so that
 25 the loop m can be engaged with the proper notch upon the catch j^2 . The lever l is then swung away from the clamp bar thus drawing said bar tightly upon the trousers and clamping them against the cross bar e . The
 30 top of the trousers is then dropped between the clamp bar h and the cross bar f ; the side bars $c-c'$ being brought forward slightly so as to insure the application of the desired stress upon the trousers. The closing and holding means for the clamp bar
 35 h is then actuated in the manner described in connection with the clamp bar g , thus clamping the trousers firmly between the bar h and the bar f . The various sections of
 40 the stretcher are then brought into alignment and the several plates p are swung into the slots o^3 in the extended edges o^2 of the distance pieces o the ends thereof engaging the wear surface q carried by the adjoining
 45 side bar. The positioning of the various plates p will define the minimum stretch to which the trousers are subjected as movement of any of the sections toward the trousers is prevented when these pieces are once
 50 set in the manner described. If it is desired to apply greater stretch to the clamps, the uppermost and lowermost sections may be forced backward or away from the trousers slightly, thus bringing the trousers against
 55 the rungs $d-d'$ and giving a slight additional stretch thereto. The act of so moving the upper and lower sections brings the clamping bars g and h beyond the vertical center of the rungs $d-d'$ and will cause the
 60 stretcher to remain in this position as the
 65

line of stress will be beyond the vertical centers of the pivotal points of these sections. While one pair of trousers is being stretched upon the device, the rungs $d-d'$ may be used as clothes hangers without any interference with the operation of the device in any way. 70

If it be desired to merely form a pair of trousers, a mere positioning of the trousers in the stretcher in the manner described, 75 will secure the desired result. If, however, it is desired to give them a well defined crease this may be secured by merely moistening the fold of the trousers while they are under stretch. 80

A garment stretcher when used in the manner above described is especially adapted for use in a wardrobe but if it be desired to crease trousers while they are packed in a traveling bag, dress suit case or other article of luggage, this may be done by mounting the trousers in the manner above described allowing a trifle slack therein, however. Then instead of using the plates p , 85 they may be left in their inoperative position, as shown in Fig. 2 and the device may be folded in a direction away from the trousers, the smallest section folding within the larger, and the larger within the largest section with the trousers therein. The presence 90 of the rungs $d-d'$ across the space within the frame will apply the requisite tension to the trousers to secure the desired stretch even while the device is folded. By damping the front and back folds of the 100 trousers a well defined crease may be secured while the folds around the rungs $d-d'$ will not be apparent when the garment is removed from the stretcher. 95

When it is desired to remove the trousers 105 the clamping bars $g-h$ are released and the trousers removed therefrom in the usual manner.

The construction of the closing and holding means for the clamping bars is such as 110 to impart to them the desired flexibility to accommodate the device to trousers, the materials of which differ in thickness, or the use of the device with two or more pairs of trousers. 115

It is not my intention to limit the invention to the precise details of construction shown in the accompanying drawings, it being apparent that such may be varied without departing from the spirit and scope 120 of the invention.

Having described the invention, what I claim as new and desire to have protected by Letters Patent is:—

1. A garment stretcher embodying there- 125 in a plurality of sections each having parallel side bars, said bars of succeeding sections being shorter in length than, and positioned within, the side bars of the adjoining section, means pivotally connecting the side 130

bars of adjoining sections, distance pieces spacing the bars of shorter length within and away from the bars upon the adjoining section, means carried by the side bars of one section coöperating with the respective distance pieces and the side bars of the other section, whereby said sections may be locked in the extended position, a cross bar carried by each end section, a clamp bar adapted to bear toward each end bar and means adapted to close and hold said clamp bar.

2. A garment stretcher embodying therein a plurality of sections, each having parallel side bars, said bars of succeeding sections being shorter in length than, and positioned within, the side bars of the adjoining section, rungs extending between and through the side bars of adjoining sections whereby said sections are pivotally connected and a rack is presented intermediate the side bars, distance pieces spacing the bars of shorter length within and away from the bars upon the adjoining section, means carried by the side bars of one section coöperating with the respective distance pieces and the side bars of the other section, whereby said sections may be locked in the extended position, a cross bar carried by each end section, a clamp bar adapted to bear toward each end bar and means adapted to close and hold said clamp bar.

3. A garment stretcher embodying therein a plurality of sections, each having parallel side bars, said bars of succeeding sections being shorter in length than, and positioned within, the side bars of the adjoining section, distance pieces each comprising a troughed fitting having one edge thereof turned to engage the side bar of one section and the other edge thereof projected beyond the side bar of the adjoining section and provided with a slot therein, and a pivotal plate mounted upon said turned edge and adapted to enter said slot and engage said last named side bar adjacent the ends and between the side bars, of adjoining sections, rungs extending between and through said distance pieces and the side bars of adjoining sections whereby said sections are pivotally connected and a rack is presented intermediate the side bars, a cross bar carried by each end

section, a clamp bar adapted to bear toward each end bar and means adapted to close and hold said clamp bar.

4. A garment stretcher embodying therein a plurality of sections each having parallel side bars, said bars of succeeding sections being shorter in length than, and positioned within, the side bars of the adjoining section, means pivotally connecting the side bars of adjoining sections, a distance piece spacing the bars of shorter length within and away from the bars upon the adjoining section, means carried by the side bars of one section coöperating with said distance piece and the side bar of the other section whereby said section may be locked in the extended position, a cross bar carried by each end section, a clamp bar adapted to bear toward each end bar and adjustable means adapted to close and hold said clamp bar whereby the clamping action of said clamp bars may be varied.

5. A garment stretcher embodying therein a plurality of sections each having parallel side bars, said bars of succeeding sections being shorter in length than, and positioned within, the side bars of the adjoining section, means pivotally connecting the side bars of adjoining sections, a cross bar carried by each end section, a clamp bar adapted to bear toward each end bar, a bracket pivotally secured to each side bar adjacent said clamp bar, and having an ear carried thereby and secured to said clamp bar, and a stepped catch projecting at an angle from the end of said bar, a bearing plate mounted upon each side bar, a lever mounted in said bearing plate and having cranks thereon, and a loop mounted on said cranks and adapted to engage said stepped catch, whereby said clamp bar may be closed and held with relation to its cross bar.

In witness whereof I have hereunto affixed my signature, in the presence of two subscribing witnesses, this 20th day of March, 1915.

DWIGHT W. CUSTER.
